UNITED STATES PATENT OFFICE.

CARL FÖLSEL, OF MUNICH, GERMANY.

GAS-PURIFIER.

No. 926,647.

Specification of Letters Patent.

Patented June 28, 1902.

Application filed June 18, 1901. Serial No. 322,298.

To all whom it may concern:

Be it known that I, CARL FÖLSEL, citizen of Germany, residing at 31 Joeselsplatz 9, Munich, Germany, have invented certain new and useful Improvements in Gas-Purifiers; and I do hereby declare the following to be a full, clear, and exact description of the invention, such as will enable others skilled in the art to which it appertains to make and use the same.

The present invention relates to an apparatus for purifying the gases coming from blast furnaces and other impure gases in order to enable them to be advantageously utilized for driving motors or to be employed in Cowper or other blast heaters.

The type of gas purifying apparatus to which this invention more specially relates is that known as centrifugal purifiers. This class of purifiers so far as hitherto known is open to the serious objection that the power necessary to drive them is very considerable and, therefore, the advantage of recovering the energy from waste gases of combustion and the like is to a very great extent rendered nugatory by the great amount of power consumed. In other words, since the object of such purifiers is to render gases which would otherwise go to waste serviceable in the production of energy and otherwise for industrial purposes, it follows as a necessary consequence that such apparatus should absorb a comparatively low amount of power, and this is exactly where the devices of this character heretofore constructed are lacking. Among the reasons for which such devices have been impractical is that they were so devised as to require a large amount of water for scouring the gases. Now it has been found that in certain examples of such centrifugal gas purifiers which required the application of one H. P. for passing about 100 cubic meters of gas without the employment of water consumed about 50 H. P. when employing only 200 liters of water in scouring, for the same amount of gas.

It is the object of the present invention to devise a centrifugal gas purifier in which the objections above outlined are overcome as far as possible, and with this object in view I have devised an apparatus now to be described in which, in the first place, the parts are so arranged that a considerable part of the kinetic energy of the gases to be treated is utilized in driving the apparatus, and in which, in the second place, the intensity of

the scouring action of the water or scouring liquid employed is very considerably enhanced, so as to make it possible to work with only a small fraction of the amount of water or other liquid heretofore necessary.

Another feature of my invention is to utilize also the force of the water or other liquid to aid in driving the apparatus.

In the accompanying drawing I have represented what I consider the preferable embodiment of my invention.

In this drawing Figure 1 represents a turbine purifier of radial construction in vertical section; Fig. 2 a similar section of the turbine wheel purifier, somewhat modified in form; Fig. 3 a similar section of the turbine wheel proper of the same; Fig. 4 a diagrammatic view to illustrate the action of the gas and water currents; and Fig. 5 a longitudinal central section of a modification embodying a purifier in which the fluids and impurities are conveyed in a substantially axial or longitudinal course.

Referring now to Fig. 1 it will be noted that the apparatus represented therein consists essentially of a turbine-wheel, L, mounted in a casing, A', said turbine being provided with curved vanes, a. Adjoining the periphery of the wheel, L, the casing, A', is provided with a series of stationary vanes, b, in the present case spaced in accordance with the spacing of the vanes, a. Besides these there are arranged with the casing a series of partitions, c, c, d, d, extending from different properly spaced portions of the periphery of the wheel, L, to the gas outlet, A, of the casing, A'. The gas inlet is at E, within the wheel, L. At W, is arranged a water-nozzle, arranged to inject water in a substantially tangential direction to the periphery of the wheel, L, said water being introduced under pressure. This water nozzle, W, is inclosed in an air-nozzle, P, so as to leave an air space all around said water nozzle, said air nozzle being supplied with compressed air. The effect of this arrangement is that the water issuing from nozzle, W, is injected into the casing in the form of a fine spray. The operation of this apparatus is as follows: The gases to be purified enter at E and pass into the casing, A', through the spaces between the vanes of the wheel L, rotating in the direction of the arrow, and in so doing they are thrown toward the exterior and at the same time, on account of the fact that the concavity of the vanes or paddles, a, is opposite to

the direction of rotation, these gases exert a force against said vanes which acts to accelerate the rotation of the wheel, a part of the kinetic energy of the gases being thus converted into pressure against the vanes. At the same time a spray of atomized water is thrown against the concave faces of the vanes, *a*, in a substantially oblique direction. A part of said spray of water passes out with said gases into the channels between the partitions, *c*, *c*, *d*, *d*, removing a part of their impurities by its suspending action and a portion by virtue of the fact that it undergoes a high degree of cooling due to expansion and vaporization and also by reason of deflection of the path traveled by said gases, according to known principles. The greater portion of the water, however, passes between the vanes, *a*, into the interior of the wheel where it meets the emerging current of impure gases traveling in an opposite direction. The greater portion of this water entering between the vanes, *a*, strikes against the concave surfaces of said vanes and propels the wheel, *L*, in the direction of the arrow and by its inertia passes in a film along the faces of the blades into the interior of the said wheel. At the same time the gases which have thus been mixed with the water are thrown out between the vanes by the centrifugal action of the same and this, combined with their pressure against the film of water flowing along the concave surfaces of the vanes, serves to thoroughly intermingle the gases with the cold water. By this action the dust and other impurities suspended in the gas will be thrown out, an action which is assisted by the deflection of the course of the hydrated gases issuing from the wheel by the stationary vanes, *b*, and by the impingement of this fluid mixture against the partitions, *c*, *c*, *d*, *d*. The final result is that the impurities in the gas will be deposited in the form of sediment at the outlet, *A*, to be caught, preferably, by a water seal as usual, while the purified gases pass on. It will be noted in this example of carrying out my invention that the course of the gas is deflected, at the outer dust zone where the same are the most densely laden with impurities by reason of the greater specific gravity of these impurities, by the fixed vanes, *b*, and by the inner ends of the partitions, *c*, *c*, *d*, *d*, which are contiguous to the wheel. Thereby they are thrown down in their further course, particularly since they are thoroughly saturated with water and the gases hence leave at the outlet, *A*, discharged of these impurities. Moreover, it is to be observed that by the fact that the concavity of the vanes, *a*, faces in a direction opposite to the movement of the wheel, a portion of the *vis viva* of these gases is converted into work by assisting the propulsion of the wheel. There is, hence, a considerable saving in the expenditure of

power to drive the wheel. Any dust which collects under the vanes will be carried off by the water coursing along these vanes.

In Figs. 2 and 3 is represented another form of carrying out this invention. In this case the turbine wheel, *L*, is provided with three concentric series of vanes, *e*, *f*, *g*, which vanes alternately curve in opposite directions, as shown, so that in the present case the middle series of vanes, *f*, has its concavity facing in a direction opposite the direction of rotation of the wheel, as indicated by the arrow, Figs. 2 and 3. There is in this case also a water nozzle or injector, *W*, arranged about tangentially to the wheel. The casing, *A'*, differs from that in the previously described modification in that here the inlet *E* for the gases as well as the outlet *A*, is outside of the wheel, the outlet being at the top and the inlet at the bottom. The casing is again divided off by the partitions, *e*, *e*, *d*, *d*, arranged in the inlet as well as the outlet portion of the casing, *A'*, said partitions ending in close proximity to the wheel and being so shaped and arranged with relation to the vanes, *e*, *f*, that they will act as means for deflecting the current of gases to be purified entering between the vanes of the wheel and issuing therefrom. In order to force the gases to flow in a substantially diametrical direction through the wheel, I arrange with the said wheel a series of stationary partitions *i*, *i*, *h*, *h*, whose general direction is vertical and whose ends adjoining the vanes of the wheel are curved so as to make the change of direction from between the vanes to between the partitions as gradual as possible. In this modification the operation is apparent from the foregoing. The gases to be purified enter at, *E*, and by the partitions *c*, *d*, are distributed over the lower half of the periphery of the wheel with considerable uniformity and in their further course they pass through between the vanes on the lower portion of the wheel, thence between the partitions *i*, *i*, *h*, *h*; and thence between the vanes in the upper portion of the wheel and thence out to the outlet *A* between the partitions *e*, *d*, *d*. On entering between the vanes in the lower portion of the wheel these gases are first impelled forward by the vanes, *e*, whose concavity faces in the direction of rotation of the wheel, *L*, and the initial velocity of these gases combined with that of the vanes, *e*, according to numeric value and direction, gives rise to a resultant velocity, which impels these gases in their further course against the concave surfaces of the vanes, *f*, with a velocity and a consequent *vis viva* which is converted into work, in adding to the propelling power of the wheel. Thereby, a portion of the energy absorbed by the gases in being hurled forward by the vanes, *e*, is restored and, moreover, a portion of the energy due to the velocity of the gases on

entering the apparatus is employed in driving the wheel. The gases then pass between the vanes, *g*, and thence between the partitions *i*, *h*, and thence in turn between the vanes, *g*, the vanes, *f*, and the vanes, *g*, where again a restoration of energy 5 consumed by the gases in being subjected to the centrifugal action of the blades, *g* and *e*, is effected by the action of the blades, *f*, whose concavities face in a direction opposite to that of the rotation of the wheel.

In Fig. 4 the combination of the velocities of the gases at their entrance between the vanes and those imparted by the vanes is 15 graphically represented. The action of the washing liquid is similar to that in the first example; it is, however, considerably enhanced by the construction and arrangement of the vanes. These vanes *e*, *f* and *g*, it will 20 be noted, do not form continuous partitions and are not exactly in line, but, as shown, they are separated, so as to leave openings between them, the vanes, *f*, in the present instance being set somewhat in advance of the vanes, *e* and *g*. This arrangement of the vanes permits the formation of a continuous film of water running along the concave surfaces of the vanes, *e*, *f*, *g*, as indicated by the arrows, *l*, in Fig. 4. Since the gases are by 25 the action of the wheel and owing to the special arrangement of the vanes, continually forced against the concave faces of these vanes, an intimate mixture of the water with the gases is brought about, whereby a great 30 part of the impurities are thrown out and carried away by the streams of washing liquid running through the wheel and out at *E*. This action of separation is, moreover, enhanced by the continually changing course of 35 the gases in passing between the vanes and the partitions *i*, *h*, the heavier particles, by 40 their inertia, seeking to maintain a straight path. This action is also assisted by the fact that the gases are alternately compressed 45 and expanded in passing first between the vanes at the lower portion of the wheel and then between those at the upper portion of the wheel. Finally the arrangement of the 50 partitions *e*, *d*, *d*, serves to deflect the gases at the outer dust zone, whereby, a great portion 55 of sediment is thrown down or separated from the same before leaving the scouring apparatus. The small amount of dust which collects under the vanes, Fig. 3, will be carried off by the water which courses along these vanes in its passage out of the apparatus. From *A* the gases may pass to the gas 60 engine or other apparatus of utilization.

In Fig. 5 I have shown a modified form of purifiers under my invention in which the action of the fluids is mainly axial or longitudinal instead of radial as in the prior views. In this figure the inlet for the gases to be purified is at *E* at the bottom of one end of the 65 drum or casing *A'*, and the outlet, *A*, at the

bottom of the opposite end. The gas on its entry into the casing and before its exit passes through annular chambers, *e'* and *a'*, within which are arranged annularly disposed nozzles, *m*, *m*, for injecting or spraying the water or other wash liquid, longitudinally into the casing, said nozzles forming part of the water injecting device, *W*, here in the form of an annular tube. The nozzles *m'*, it will be noted, are nearer to the center or axis 70 of the purifier than the nozzles *m* for a purpose which will be explained below. On the rotary shaft, *J*, are mounted a number of disks or other supports, *k*, *k*, *k*, on the peripheries of which are mounted the vanes or blades, *l*, 75 whose curvature is arranged relatively as in the case of the vanes, *e*, *f*, *g*, of Fig. 3, the difference being that in the present case this arrangement is longitudinal instead of radial. These vanes, *l*, besides the longitudinal curvature just described have a curvature in a radial direction, as best shown in Fig. 5, that is, their outer free ends are bent over in the direction of rotation so as to prevent the water deposited on them from being thrown 80 against the walls of the casing under the action of the centrifugal force. There are besides mounted on the disks a series of blades or vanes, *g*, which lie only in the outer dusty zone of the drum. These blades or vanes, *g*, 85 have such a curvature that they move the washing liquid in the outer dusty zone, and, in fact convey the matter accumulating in the said zone in the direction of the arrows, *1*, that is to say, opposite to the direction in 90 which the gases are conveyed by the vanes, *l*, which latter direction is indicated by the arrows, *2*, in said Fig. 5.

This apparatus operates as follows: The gases to be washed enter at *E* and then pass 105 in an annular stream between the vanes, *l*, toward the outlet. As they issue from the annular chamber, *e'*, they are mixed with the wash liquid sprayed from the nozzles *m'*. This and the change of direction of their 110 course serves to throw out a portion of the impurities. On passing between the vanes coated with a film of water as under the construction of Fig. 3, the same separation, and also the same recovery of power, by virtue 115 of certain vanes having their convexity opposite to the direction of rotation, takes place, as under that construction. The deflecting means at the outer dust zone under the present modification consist in part in 120 the nozzles, *m*, which inject a longitudinal stream of wash liquid into this zone in a direction opposite to the movement of the gases, but more particularly in the vanes, *g*, in the outer dust zone, which have a 125 curvature such as to convey the dust and impurities there accumulating in a direction opposite to the course substantially taken by the gases under the influence, in part, of the vanes or blades, *l*. By this action the 130

separated dust and impurities accumulating in this zone are effectually brushed aside and thrown down and thus separated from the gases before they issue at the outlet A. 5 This cleaning action is materially assisted by the supplemental vanes, q , q , above described, arranged in the dust zone and which serve to insure the contact of the gases in this dust zone with a sufficient liquid film surface 10 to thoroughly clean them.

It will be seen from the above description that in each of the various forms of purifier shown and described for carrying out this invention there are provided means for causing 15 the gases to be purified to travel in one direction and to impart thereto a centrifugal movement and also means, acting in conjunction therewith, for causing the impurities or other matter collecting in the outer 20 dust-zone to travel in a direction opposite to the general direction taken by the gases while being purified.

While I have described herein and shown 25 in Fig. 5 a longitudinally or axially acting purifier in further illustration of my invention, generically considered, I do not herein claim the same specifically, since thus viewed it forms the subject matter of a copending application. Said copending application 30 was filed February 25, 1909, and has the Serial Number 479998.

Having thus fully described my invention, what I claim and desire to secure by Letters Patent is:—

35 1. In a gas purifying apparatus, the combination of means for treating a gas which flows in one direction whereby a centrifugal movement is imparted to said gas and to the matter entrained therein, said means causing 40 the formation of an outer dust zone wherein the collecting matter may flow in a direction substantially opposite to the general direction of travel of the gases, and means for injecting wash liquid, said injecting means 45 being so positioned to coöperate with the first-mentioned means as to direct the general travel of the wash liquid through said first mentioned means in a direction substantially opposite to the course of the gas.

50 2. In a gas purifying apparatus, a rotary wheel provided with vanes in combination with a gas inlet, arranged to admit the gases to be purified in the direction of the rotation of said wheel, and a water inlet arranged at a 55 point opposite to the gas inlet but so as to admit the water in the direction of said rotation.

3. In a gas purifying apparatus, a rotary

drum provided with a number of concentric series of vanes, the vanes of each series being curved oppositely to the vanes in the adjoining series, in combination with a gas inlet for admitting gas to said drum, and a gas outlet leading from said drum opposite the gas inlet.

4. In a gas purifying apparatus, a rotary drum provided with a number of circular series of vanes, the vanes of each series being curved oppositely to the vanes of the adjoining series, in combination with a gas inlet and a gas outlet arranged at opposite points of said drum.

5. In a gas purifying apparatus, a rotary wheel provided with a number of concentric series of vanes, the vanes of each series being curved oppositely to those of the adjoining series and openings being provided between each two series of vanes in combination with a gas inlet directed against said wheel.

6. In a gas purifying apparatus, a rotary drum provided with a number of concentric series of vanes having openings between the vanes of each series, the vanes of each series being curved oppositely to those of the adjoining series, in combination with a gas inlet directed against said drum and an oppositely directed water injector arranged at an opposite point of said drum.

7. In a gas purifying apparatus, a rotary drum provided with a concentric series of vanes, the vanes of alternate series being set back and oppositely curved with relation to those of the other series so as to leave openings between the adjacent vanes, in combination with a gas inlet directed against said drum, and an oppositely directed water injector arranged at an opposite point of said drum.

8. In a gas purifying apparatus, the combination with a supply of gas, of revolving vanes acting upon the gas to form a dust zone, a liquid injecting device to supply finely divided wash water to the vanes in the region of the dust zone, and means adapted to so coöperate with said liquid injecting device as to direct the general travel of the mixture of wash liquid and dust past said vanes in a direction substantially opposite to that of the gas current passing therethrough.

In testimony whereof I hereunto affix my signature in the presence of two witnesses.

CARL FLÖSSEL.
